UNITED STATES PATENT OFFICE.

HARRY F. GEORGE, OF CHICAGO, ILLINOIS.

ACCELERATOR.

Application filed June 22, 1921. Serial No. 479,475.

To all whom it may concern:

Be it known that I, HARRY F. GEORGE, a citizen of the United States, residing at Chicago, in the county of Cook and State 5 of Illinois, have invented certain new and useful Improvements in Accelerators, of which the following is a specification.

This invention relates to a new and improved throttle operating device or accelerator for automobiles, and more particularly to a device of the character described especially adapted for use in connection with cars having control pedals operated similarly to those in use upon the Ford car.

15 In the operation of an automobile it is highly desirable to open the throttle valve and thus accelerate the engine when going into the low gear or into the reverse gear, which latter is a low gear simply operating 20 in the reverse direction. This acceleration is necessary to afford the desired power and to avoid the possibility of stalling the engine. With cars of the ordinary type the throttle control is operated by a lever located upon the steering column and on going into low gear with such machine it is necessary to do two separate things, namely, 25 manipulate the necessary pedals and at the same time manipulate the throttle lever.

30 In some machines provision for this opening of the throttle or accelerator has been made by means of a separate pedal. This, however, although it avoids the necessity for using the hands at that time, still retains the requirement for the doing of two 35 things at once. Means, therefore, which are adapted to open the throttle and accelerator of the engine automatically upon going into either low speed or the reverse, are highly 40 desirable.

The use of either of these gear connections is ordinarily only temporary and at the end of their use it is desirable to return to the previous adjustment of the throttle valve.

45 Any variation, therefore, caused automatically by the drive control levers upon the adjustment of the throttle valve should be entirely independent of the adjustment caused by the usual manual throttle control 50 lever, and should permit return to the adjustment of that lever automatically upon coming out of the slow speed or reverse position.

It is an object of the present invention to 55 provide a throttle control device adapted to be connected to the vehicle drive control

levers in such manner as to automatically open the throttle upon predetermined movement of those levers.

It is a further object to so connect the 60 control to the throttle as to cause it to open the throttle independently of the hand throttle adjustment.

It is an additional object to provide means 65 associated with the device to return all parts to their previous position, that is, the position determined by the adjustment of the hand control, upon release of the levers.

It is a further object to provide in connection with such an accelerator, means for 70 operating it by a foot pedal independently of other control means.

It is also an object to provide a device which is simple in design, relatively inexpensive in construction and which may be 75 readily applied to existing automobiles without modification thereof.

It is another object to provide a pedal particularly adapted for use with devices 80 of this character.

Other and further objects will appear as the description proceeds.

Broadly, my invention comprises a shaft 85 adapted to be located adjacent the drive control levers of a vehicle, the shaft having means connecting it to certain of said levers in such manner that the shaft is rotated by movement of the levers in one direction. The shaft is further provided with an arm and a pedal is associated therewith in such 90 manner as to operate the shaft independently of the vehicle drive levers. Means are further provided for returning the shaft to its previous position upon release by the levers or pedal. The particular form of 95 connection to the throttle is such as to permit adjustment of the throttle by the usual hand levers independently of the device.

I have illustrated a preferred embodiment 100 of my invention in the accompanying drawings, in which—

Figure 1 is a somewhat diagrammatic view of an engine and its associated control levers with my device applied thereto;

Figure 2 is a plan view of my device; and 105

Figure 3 is a view in section showing my special pedal.

The engine and control levers shown in the figure are similar in type to those in use upon the Ford automobile and the particular embodiment shown is especially adapted for use in connection with that ma 110

chine. It obviously, however, may be modified to adapt it to other motors and control devices.

As shown in Figure 1, the engine 4 has 5 associated therewith the carburetor 5 having the throttle lever 6. The gear housing 7 is provided at its upper side with the closure plate 8. To this plate 8 is secured the holding bracket 9 of my device. This 10 bracket is provided with two journals 10 through which passes the shaft 11. This shaft is provided with the crank 12 upon its left end, as shown in Figure 2. The lugs 13 and 13' are secured to the crank 12 by 15 means of the set screws 14 and 14'. Pivoted to each of these lugs are the lateral extensions 15 and 15' which are perforated to receive the rods 16 and 16'. These rods 20 carry the sleeves 17 and 17' adjustably secured thereto by the lock screws 18 and 18'. Pivoted to the rods are the loops 19 and 19' which are adapted to engage the shanks of the forward and reverse pedals 20 and 21 respectively. The arm 22 is fitted 25 upon the shaft 11 between the journals 10 and is held in the desired angular relation therewith by the set screw 23. The arm 22 carries at its upper end the roller 24 which is adapted to be engaged by the wear plate 25 upon the lower surface of the pedal 26. The collars 27 and 27' are retained in place 30 upon the shaft 11 by the set screws 28 and 28' in such position as to engage the journals 10 and prevent lateral displacement of 35 the shaft.

Upon the right end of the shaft 11 is secured the arm 29. This arm is provided with the upwardly extending lug 30 to which is connected the spring 31. To the end of the 40 arm is secured a ball socket 32 into which fits a ball 33 carried by one end of the rod 34. The opposite end of the rod 34 carries a ball 35 fitted in a ball socket 36 which is fastened to the throttle lever operating arm 45. This arm 37 is provided with the screw 38 adapted to connect the member to the throttle lever 6 and is further provided with downwardly depending lugs 39 and 39' adapted to engage the lever to prevent displacement therefrom. The member 40 is 50 pivotally carried by the member 37 and is perforated to receive the control rod 41 which is adapted to be connected to the usual manual control device of the machine. The rod 41 is provided with the enlarged 55 head 42 which bears upon the member 40.

The pedal, as shown in detail in Figure 3, comprises the heel portion 43 and sole portion 44, the latter being at a higher level. 60 It is pivotally connected to the support 45 by the transverse pin 46. The spring 47 is connected to the support 45 at 48 and engages the undersurface of the foot portion. The bearing plate 25, as previously stated, 65 is secured to the lower face of the foot

portion and adapted to engage the roller 24. The pedal and its support are preferably formed of aluminum alloy while the wear plate is formed of steel.

In the operation of my device, it will be 70 seen that inward movement of either pedal 20 or 21 will move the rod 16 or 16' inwardly, or upwardly as shown in Figure 2. The corresponding collar 17 or 17' will engage the member 15 or 15' and will thus 75 rotate the shaft 11 about its pivot in the journal members 10. This rotation of the shaft will be against the tension of the spring 31 connected to the portion 30 of the arm 29. This arm 29 will be thrust 80 downwardly and its movement will thrust the rod 34 forwardly. This movement of the rod will be transferred to the member 37 through the ball connection therewith and will serve to rotate the throttle control lever to the left, as seen in Figure 2. In this movement the member 40 will slide 85 on the rod 41 and the adjustment of the manual control rod 41 will not be disturbed.

Upon release of pressure upon the pedal, and consequently through the collar 17 or 17', upon the shaft, the spring 31 will 90 rotate the shaft until the member 40 engages the head 42 on the manual control rod. The throttle adjustment is then 95 restored to that point prior to the acceleration. If not stopped by the engagement between these members 40 and 42, the rotation of the shaft would be stopped by engagement of either lug 15 or 15' with its 100 coaxing sleeve or by engagement of the roller 24 with the wear plate 25 on the pedal 26. However, the adjustment of the several parts is preferably such that under 105 normal conditions the members 15 and 15' do not engage the sleeve nor the roller 24, the pedal.

If it is desired to accelerate the motor independently of movement of the pedals 20 or 21, this may be accomplished by depressing 110 the forward end of the pedal 26. The contact member 25 engages the roller 24 and rotates the shaft 11, whereupon the adjustment of the throttle is accomplished as before described. Upon release of the 115 pedal the spring 31 carries the parts back to the previous adjusted position.

It will be observed, of course, that movement of the rod 41 in order to vary the 120 throttle will of necessity move the member 30 and consequently when moving to the left or opening the throttle this movement will be against the tension of the spring 31. However, the leverages are such that this spring will not make the movement of 125 the hand lever unduly hard. On the other hand, when closing the throttle the rod 41 does not positively move the throttle, but upon its movement to the right the tension of the spring 31 serves to keep the member 130

40 against the member 42 and the spring thus closes the throttle.

The pedal shown in Figure 3 is simple in design and relatively inexpensive to construct, and it has the important advantage that the foot is positively supported in the normal position in which it is shown, and sudden direct pressure upon the pedal will not accelerate the engine. It is necessary 10 to tilt the foot, depressing the toe, in order to accomplish this result. This operation thus being different from the usual pedal on the machine, there is no danger of inadvertently accelerating the machine when 15 the intention, for example, is to apply the brake.

My device is extremely simple in design and the form shown may be readily applied to existing Ford machines without any material variation in the machine and at comparatively small expense and in a very short 20 time.

I claim:

1. In combination with the drive control 25 levers and throttle valve of an automobile, a shaft located adjacent said levers and operatively associated with the throttle valve, a perforated lug on said shaft adjacent each lever, a rod connected to the lever and passing 30 through the perforation, a collar on said rod adapted to engage the lug to rotate the shaft upon movement of a lever, said movement serving to operate the throttle valve, and means adapted to return the 35 shaft to its previous position upon release of said lug by said collar.

2. In combination with the drive control 40 levers and throttle valve of an automobile, a shaft located adjacent said levers and operatively associated with the throttle valve, a perforated lug on said shaft adjacent each lever, a rod connected to the lever and passing 45 through the perforation, a collar on said rod adapted to engage the lug to rotate the shaft upon movement of the lever, said movement serving to operate the throttle valve, an arm on said shaft and a pedal adjacent said arm and adapted to engage 50 the arm to rotate the shaft, and means adapted to return the shaft to its previous position upon release of said lug by said collar and of said arm by said pedal.

3. In combination with the drive control 55 levers and throttle valve of an automobile, a shaft located adjacent said levers and operatively associated with the throttle valve, a perforated lug on said shaft adjacent each lever, a rod connected to the lever and passing 60 through the perforation, a collar on said rod adapted to engage the lug to rotate the shaft upon movement of the lever, said movement serving to operate the throttle valve, an arm on said shaft and a pedal adjacent said arm and adapted to engage 65 the arm to rotate the shaft, and a spring

connected to a lug upon the shaft adapted to return the shaft to its previous position upon release of said lug by said collar.

4. Control mechanism for automobiles of the Ford type comprising a rotatable shaft 70 having an offset crank portion, adjustable members mounted upon said offset crank portion, said members being provided with rotatable perforated members, rods adapted to extend through said perforated members 75 and being provided with adjustable stop means, said rods being adapted to be connected to the low speed and reverse pedals of a Ford motor car, a bracket adapted to be mounted upon the body of a motor car and adapted to support said rotatable shaft, collars mounted upon said shaft for preventing the longitudinal movement of said shaft relative to said bracket but permitting rotary movement of said shaft, throttle control means, means for communicating motion from said rotatable shaft to said throttle control means, and a control rod having a 80 lost motion connection with said throttle control means.

5. Control mechanism for automobiles of the Ford type comprising a rotatable shaft 85 having an offset crank portion, adjustable members mounted upon said offset crank portion, said members being provided with rotatable perforated members, rods adapted to extend through said perforated members and being provided with adjustable stop means, said rods being adapted to be connected to the low speed and reverse pedals 90 of a Ford motor car, a bracket adapted to be mounted upon the body of a motor car and adapted to support said rotatable shaft, collars mounted upon said shaft for preventing the longitudinal movement of said shaft relative to said bracket but permitting rotary movement of said shaft, an arm non-rotatably secured to said shaft, and a pedal 95 for operating said arm, said pedal being biased to a predetermined position such that 100 a predetermined selective direction of pressure is required on said pedal before said pedal can operate said arm.

6. Control mechanism for automobiles of the Ford type comprising a rotatable shaft 115 having an offset crank portion, members mounted upon said offset crank portion, said members being provided with rotatable perforated members, rods adapted to extend through said perforated members and being provided with adjustable stop means, said rods being adapted to be connected to the low speed and reverse pedals 120 of a Ford motor car.

7. Control mechanism for automobiles of the Ford type comprising a rotatable shaft 125 having an offset crank portion, members mounted upon said offset crank portion, said members being provided with rotatable perforated members, rods adapted to extend 130

through said perforated members and being provided with adjustable stop means, said rods being adapted to be connected to the low speed and reverse pedals of a Ford motor car, a bracket adapted to be mounted upon the body of a motor car and adapted to support said rotatable shaft, collars mount-

ed upon said shaft for preventing the longitudinal movement of said shaft relative to said bracket for permitting a rotary movement of said shaft.

Signed at Chicago, Illinois, this 8th day of June, 1921.

HARRY F. GEORGE.
